UNITED STATES PATENT OFFICE

JOHN R. BROOKS, OF RICHMOND, VIRGINIA

SIGNAL DEVICE

Application filed December 17, 1930. Serial No. 502,936.

This invention relates to railway trains, and more particularly to signal devices therefor. The principal object of the invention is the provision of a new and improved signal device for railway trains, together with novel means for mounting the same thereon.

Another object of the invention is the provision of a new and improved signal flag for railway trains and the like having novel means for supporting the same so that the flag will be visible from the front or rear of the train as well as from the side thereof.

A further object of the invention is the provision of a new and improved signal flag arrangement for railway trains, together with novel means for mounting and housing the flag, whereby the same is properly located on the train and ready at all times to be moved into operative or inoperative position, as occasion may require.

A still further object of the invention is the provision of a new and improved signal device that is inexpensive to manufacture, that may be readily attached to the train without making any changes in the conventional equipment, that is efficient in operation, and that may be installed at a minimum of labor and expense.

Other and further objects and advantages of the invention will appear from the following description taken in connection with the accompanying drawings, in which

Fig. 1 is a top plan view of a locomotive showing the same more or less diagrammatically and showing the invention in position thereon;

Fig. 2 is a top plan view of the bracket for supporting the device, showing the invention in position thereon;

Fig. 3 is a front elevation of the same, showing the invention in its operative position;

Fig. 4 is a side elevation of the casing for the classification flag, showing the latter in operative position, and with parts broken away;

Fig. 5 is a section on line 5—5 of Fig. 4;

Fig. 6 is a perspective view of the outer or free edge of the casing, with parts broken away; and

Fig. 7 is a section on line 7—7 of Fig. 5.

It is the common practice to provide trains with signal devices, such as classification flags, for signaling from moving trains certain information to the employes along the road. For instance, when the train is run in sections, the engine of each section usually carries what is called a classification flag, in the daytime, and at night a lamp, of a particular color indicating such fact, and the last section will carry a flag or lamp of a still different color for indicating to the switchmen and engineers on the siding that it is the last section of the train. These flags are usually made of cloth, but such signals are more or less objectionable because when the train is in motion they are scarcely visible from the front or rear, and when the train is running at high speed the employes on a train on a siding have but a few moments within which to note the signal.

The present invention seeks to remedy these defects by the provision of a new and improved signal flag that is visible from the front and rear of the train as well as from the side thereof.

Reference may now be had to the drawings, which illustrate one embodiment of the invention, selected for illustrative purposes only.

On the drawings, the reference character 10 designates the top plan view of a locomotive shown more or less diagrammatically, the smokestack being shown at 11 and the classification lamps on the front of the locomotive at 12 and 13. These lamps are supported by brackets 14 and 15 of the conventional type, each of which comprises the base 16 which is adapted to be attached to the locomotive, the arm 17 and the base plate 18.

The classification lamps are adapted to be supported on the plate 18 and in the conventional construction the lamp bases are provided with projections or feet 19 having apertures therethrough which are adapted to align with corresponding apertures 20 in said plate. Bolts 21 extending through the feet and the apertures 20 in the plate are adapted to secure the classification lamps in position on the bracket.

These lamps are provided with forwardly facing lenses 22 and 23 and with laterally facing lenses 24 and 25. The brackets 14 and 15 are each provided with a flag staff socket 5 26.

Since the specific structure of the classification lamp and its supporting bracket is of the conventional form, it is not thought necessary to further illustrate or describe the 10 same.

The improved signal device and the means for supporting the same will now be described. This device comprises a casing 27 which is adapted to be supported in a vertical position from its lower end. The casing is open at one side edge as at 28 and at its upper end as at 29. The casing comprises two plates, 31 and 32, which are held spaced apart by the bar 33 which extends along the inner side edge and bottom of the plates. The plates preferably have their lower inner corners cut away as at 34 to provide clearance for the base of the brackets 14 and 15.

The casing 27 is provided with a closure 35 at its upper end. This closure is pivoted at its inner end as at 36 and extends over the upper ends of the plates at the sides and outer edges thereof as shown at 40 in Fig. 4 of the drawings. The inner edge 30 of the closure is 20 adapted to constitute a stop for limiting the opening movement of the closure.

A plurality of plates having signal characteristics such as the colored plates 37 and 38 are pivoted at their lower outer corners as at 39 to the casing 27. These plates correspond to the shape of the casing having one corner cut away as at 41 to accommodate the cut-away portion 34 of the casing. They are adapted to be swung to a position within the 20 casing as indicated in Fig. 6, or to a position without the casing, as shown in Fig. 4.

The bar 33 is extended outwardly and is bifurcated or provided with a recess 42 for receiving the lower edge of the plates 38 for holding the same in operative position. These plates are preferably though not necessarily of sheet metal, but in any event they are substantially rigid. The sides of the casing 27 are cut away as at 43 to provide recesses in order that the plates may be more readily grasped for moving them to operative position. Where a plurality of plates are employed the plates may be provided with cutaway portions 44, 45 registering with the 55 cutaway portions of the casing, but out of register with the cutaway portions of adjacent plates, to provide clearance for the fingers whereby any one plate may be more readily moved to operative position.

60 The plates are loosely mounted on their pivots so that each of the plates may be moved to the position to engage the recess 42 of the extension of the bar 33 whereby the same will be held in operative position. The 65 plates are movable to a position within the

casing and when in such position the closure 35 will engage the upper ends of the plates and prevent their movement out of the casing.

Suitable means are provided for supporting the casing on the classification bracket. A bracket 46 is provided for this purpose. This bracket comprises a bar 47 having apertures therein through which the bolts 21 may extend for clamping the bar against the under side of the plate 18 as shown in Figs. 2 and 7 of the drawings. The bar is provided with a depending portion 48 which is adapted to engage one side of the casing and be secured thereto in any suitable manner as by 80 means of the rivets 49. The lower end of the bar may, if desired, be bent beneath the casing as shown at 51 in Fig. 7.

When the bracket 46 with the casing attached thereto is in position on the classification bracket as shown in Fig. 1 of the drawings, the casings will be supported in a plane extending diagonally to the longitudinal center line of the locomotive so that when one of the signal plates 37 or 38, which for convenience of description may be termed a classification flag, is moved to operative position, it will be visible from the front and rear of the train as well as from the side thereof. These plates are adapted to be colored, as required for classification flags, and are used in the same manner. When these flags are used, the usual cloth flag will be dispensed with.

The classification lamps 12 and 13 may be 100 provided with light openings or lenses 52 and 53 respectively whereby the flags 37 and 38 may be illuminated when in operative position so that they may be used at night if desired.

When it is desired to move one of the flags to operative position the closure 35 is elevated and the desired flag is turned to the horizontal position as shown in Fig. 4 with its edge engaging in the recess 42.

When it is desired to move the flag to inoperative position it is moved upwardly and the upper edge coming in contact with the closure 40 will elevate the closure automatically which will, when the flag is within the casing, drop to the position shown in Fig. 4, for holding the flags within the casing.

I claim as my invention:

1. In combination, a casing, a flag comprising a colored plate, means for movably connecting said plate to said casing whereby the same may be moved to inoperative position within said casing or to operative position without said casing, a lamp bracket, and means for supporting said casing from one side of said bracket.

2. In combination, a flag supporting bracket adapted to be supported on the forward portion of a locomotive, an oblong casing, means for mounting said casing on said 130

- bracket in a plane at an angle to the longitudinal axis of said locomotive to face forwardly and outwardly, a classification flag comprising a plate, means for pivotally connecting the lower outer corner of said plate to said casing whereby said plate may be swung from inoperative position within said casing through substantially 90° to operative position without said casing, and means 5 for engaging the upper end of said plate for holding the same in inoperative position within said casing.
3. In combination, a casing open along one end and one side thereof, a pivot for a 15 flag plate at the lower end of the side slot, the slotted side edges of said casing being provided with recesses adjacent their upper ends, and a closure for the end slot, said closure being adapted to extend across the top 20 of said casing and having a depending portion extending in front of the side slot for retaining said flag plate within said casing when the same is moved to inoperative position.
- 25 4. In a device of the class described, a casing, a plurality of signal devices, each device comprising a colored plate, means for pivotally connecting the lower outer corner of each plate to said casing whereby said 30 plates may be turned outwardly from said casing to operative position or turned to inoperative position within said casing, and a hinged closure for the upper end of said casing, said closure constituting means for 35 holding said plates in inoperative position within said casing.
5. In combination, a lamp supporting bracket adapted to be mounted on a railway train, a casing, means for supporting said 40 casing from said bracket, a signal flag comprising a plate having signal characteristics, means for movably connecting said plate to said casing whereby the same may be moved without said casing to a position in a plane 45 at an angle to the longitudinal axis of the train or to an inoperative position within said casing.
6. In combination, a flag supporting bracket adapted to be mounted on a railway train, a casing open at one side and at 50 its upper end, means for supporting said casing from said bracket, flag plates pivoted to said casing and adapted to be turned to a position within said casing or to operative 55 position without said casing, and a supporting arm secured to said bracket and to one side wall of said casing, and extending beneath said casing for assisting in supporting the same, said arm extending rearwardly and inwardly toward the center line of 60 said train when said bracket is in position thereon, and said casing extending in a plane at substantially right angles to said arm.
7. A casing for railway signal flags comprising a pair of side plates, a bar between 65
- said plates extending along one side edge and across the lower ends of said plates, said bar extending outwardly beyond said casing and turned upwardly and provided with a recess in the upturned portion, the free side 70 edges of said casing having portions cut away, a plurality of signal plate members pivoted at their lower outer corners to said casing and adapted to be turned downwardly for engaging said recess or to inoperative 75 position within said casing, a closure for the upper end of said casing, said closure having a depending portion for holding said signal plates within said casing, said last-named plates having cut-away portions in 80 alignment with the cut-away portions of said casing but out of alignment with each other for providing finger clearance for grasping said plates.
8. A casing for classification flags comprising a pair of side plates, a bar between said plates extending along one side edge and across one end of the same, said bar having an extension provided with an upturned bifurcated end and a closure hinged to one 90 end of said casing and having a depending flange for extending over the upper ends of said plates.
- In testimony whereof I affix my signature.
